CARL R. KLOK, OF CHICAGO, ILLINOIS.

TABLE-WAGON.

1,171,343.

Specification of Letters Patent.

Patented Feb. 8, 1916.

Application filed April 3, 1915. Serial No. 18,912.

To all whom it may concern:

Be it known that I, CARL R. KLOK, a citizen of the United States of America, and resident of 7508 Garrison avenue, Chicago, Cook county, Illinois, have invented a certain new and useful Improvement in Table-Wagons, of which the following is a specification.

My invention relates to table-wagons of that kind in which a body forming the table is mounted on wheels and adapted to be moved about in the house and employed for various purposes.

Generally stated, the object of my invention is to provide a table-wagon of this kind having means for adapting it for use in various ways and for various purposes that are not possible with the table wagons heretofore known and used.

A special object is to provide a folding table-top which can be adjusted to adapt the structure for use in various ways, and whereby, for example the table-wagon may be used as a desk, as a serving table, or as an ordinary table, as will hereinafter more fully appear.

It is also an object to provide certain details and features of construction and novel combinations tending to increase the general efficiency and desirability of a table-wagon of this particular character.

To the foregoing and other useful ends my invention consists in matters hereinafter set forth and claimed.

In the accompanying drawings—Figure 1 is a perspective of a table-wagon embodying the principles of my invention. Fig. 2 is an enlarged front elevation of the same. Figs. 3 and 4 are enlarged detail sectional views of the front and rear wheel mountings. Fig. 5 is a section on line 5—5 in Fig. 2, showing the front portion of the table top extended to form a desk, in dotted lines, and showing the bread-board and the towel-sticks extended outward in dotted lines. Fig. 6 is an end elevation of the said table-wagon showing the drawer, the towel-sticks and the bread-board all extended in full lines. Fig. 7 is a perspective of a section of one end wall of a table wagon, showing the adjacent portions of the towel-sticks, and illustrating the manner in which they are mounted.

As thus illustrated, my invention comprises a base or lower shelf A provided at each end with a vertical end wall B and C, the latter being provided at their lower ends

with base boards b and c to provide sufficient thickness for the wheel mountings. The front wheels D are provided with forks d having stems E that are fixed in the base board b and the rear wheels F have curved forks f provided with stems G that are swiveled or mounted to turn in the base board c, whereby the front wheels always remain parallel with the body of the structure, while the rear wheels are adapted to caster or turn freely to permit the table-wagon to be steered or moved easily in various directions.

A shelf H is positioned a distance across the base or shelf A, being supported at its ends by cleats h, which latter are in turn supported by cleats I on the end walls of the table body. The bread-board J has its ends provided with tongues j to engage grooves formed along the edges of the cleats h, whereby the said bread-board can be removed and placed on top of the table when it is desired to use the same.

A shelf K is arranged a distance above the shelf H, being suitably supported on the end walls B and C, and forming a support for the drawer L which is provided with a handle l at the front or outer side thereof. The towel-sticks M are arranged in pairs and pivotally supported by brackets m secured to the end walls of the table body, whereby these towel-sticks are adapted to be folded to a substantially concealed position immediately below the shelf K, as shown in the drawings.

The table-top comprises a fixed middle section N which is the same in width as the end walls B and C, and which rests on the upper end of the latter, being suitably secured thereto. A front leaf O is hinged to the front edge of the top section N at o, and is provided with parallel end strips P on the under side thereof, which strips are arranged in position to engage the edges of the end walls B and C when said leaf is swung into the plane of the table-top, whereby the area of the latter is extended at the front thereof. The rear leaf Q is pivoted at q at the rear edge of the table-top, and this leaf is provided with end strips R which engage the rear edges of the end walls B and C, when the leaf is swung into the horizontal plane of the table-top; and in addition the rear leaf has a guard or back strip r which connects together the end strips R, and which forms the back rail of

the table-top when the two leaves are in folded position, and more especially when the front leaf only is unfolded and the structure is in use as a desk. When both leaves are extended, the structure is then adapted for use as an ordinary table. The strips P form an unobstructed way for the drawer I, so that the latter may be moved out-and-in when the table top is extended. (See Fig. 5.) The two leaves when folded provide a narrow table-top which can also be used for various purposes, either in the kitchen or in the dining room. When folded the portions P, R and r form a raised margin for the table top to prevent dishes or other articles from sliding off.

It will also be seen that the structure as a whole is adapted for use as a book case, it being possible to stand one row of books on 20 the shelf A, another on the shelf H, and a third row on the top formed by the two folded leaves.

A table-wagon, when constructed as shown and described, is not only useful for 25 various purposes in the kitchen, in the dining room, and the other parts of the house, but can also be used in the laundry, as will be readily understood.

The towel rack S is supported by brackets 30 s on the wall C, immediately below the overhanging end of the top, thus serving as a handle to move the table-wagon about the house.

What I claim as my invention is:—

35 1. A table-wagon comprising a body having upright end walls, a bottom connecting said walls, a pair of wheels for the lower end of each wall, and a top connecting the upper ends of said walls and provided with 40 an upwardly folding extension leaf.

2. A table-wagon comprising a body having upright end walls, a bottom connecting said walls, a pair of wheels for the lower end of each wall, and a top connecting the 45 upper ends of said walls, said top having a pair of extension leaves hinged to the opposite edges thereof, said leaves being arranged to swing over and rest with their outer edges together on said top.

50 3. A table-wagon comprising a body having upright end walls, a bottom connecting said walls, a pair of wheels for the lower end of each wall, and a top connecting the upper ends of said walls, said top having a 55 pair of extension leaves hinged to the opposite edges thereof, said leaves being arranged to swing over and rest with their outer edges together on said top, said leaves having end strips to engage said walls and 60 thereby hold the leaves in horizontal position.

4. A table-wagon comprising a body having upright end walls, a bottom connecting said walls, a pair of wheels for the lower end of each wall, and a top connecting the 65

upper ends of said walls, said top having a pair of extension leaves hinged to the opposite edges thereof, said leaves being arranged to swing over and rest with their outer edges together on said top, said leaves having end strips to engage said walls and thereby hold the leaves in horizontal position, and one only of said leaves having an outer edge strip on the bottom thereof to form a rear guard for the top when the 75 leaves are folded, said end strips forming right angle extensions of said guard when the leaves are folded.

5. A table-wagon comprising a body having upright end walls, a bottom connecting 80 said walls, a pair of wheels for the lower end of each wall, and a top connecting the upper ends of said walls, said top overhanging said walls, brackets on one wall immediately below the overhanging end of said top, and 85 a handle connecting said brackets, serving also as a towel rack.

6. A table-wagon comprising a body having upright end walls, a bottom connecting 90 said walls, a pair of wheels for the lower end of each wall, and a top connecting the upper ends of said walls, said top having an extension arranged to fold thereon to form a desk.

7. A table-wagon comprising a body having upright end walls, a bottom connecting 95 said walls, a pair of wheels for the lower end of each wall, and a top connecting the upper ends of said walls, said top having an extension arranged to fold thereon to provide a receptacle for dishes and other articles.

8. A table-wagon comprising a body having upright end walls, a bottom connecting 100 said walls, a pair of wheels for the lower end of each wall, and a top connecting the upper ends of said walls, a drawer below 105 said top, and extension leaves for said top, foldable thereon, one of said leaves being provided with a strip to form a rear guard for the top when folded, and the other of said leaves being constructed to form an unobstructed way for said drawer when in unfolded position.

9. A table-wagon comprising a body having upright end walls, a bottom connecting 115 said walls, a pair of wheels for the lower end of each wall, and a top connecting the upper ends of said walls, and towel sticks pivoted on said body, arranged to swing 120 under said top.

10. A table-wagon comprising a body having upright end walls, a bottom connecting 125 said walls, a pair of wheels for the lower end of each wall, and a top connecting the upper ends of said walls, a shelf spaced a distance below said top, and a removable board slidably inserted under said shelf.

11. A table-wagon comprising a body having upright end walls, a bottom con- 130

necting said walls, a pair of wheels for the lower end of each wall, and a top connecting the upper ends of said walls, said walls having base boards provided with sockets, 5 and said wheels having stems inserted in said sockets, the rear wheels being allowed to caster freely by turning of their stems in the sockets thereof.

12. A folding table-wagon comprising a body having a fixed top-section, a movable extension top - section disposed over said fixed top-section, arranged to shift outside one edge of said fixed top-section, means to support said movable top - section in the 15 plane of said fixed top-section, and means to support said fixed top-section.

13. A folding table - wagon comprising a body having a fixed top - section, a movable extension top - section disposed over said fixed top - section, arranged to shift outside one edge of said fixed top - section, means to support said movable top - section in the plane of said fixed top - section, and means to support said fixed top - section, said movable top - section occupying a portion of the area of the fixed top - section, and a similar movable top - section for the other edge of said fixed top - section, the two movable sections being tight together when in non- 25 extended position.

14. A table - wagon comprising a body having a fixed top - section, a movable extension top - section disposed over said fixed top - section, arranged to shift outside one 30 edge of said fixed top - section, means to support said movable top - section in the plane of said fixed top - section, and means to support said fixed top - section, said movable section providing a horizontal surface

for dishes or other articles when in non-extended position. 40

15. A folding table-wagon comprising a body having a fixed top-section, a movable extension top - section disposed over said fixed top - section, arranged to shift outside one edge of said fixed top-section, means to support said movable top - section in the plane of said fixed top - section, and means to support said fixed top - section, said movable section being provided with edge portions which form a raised margin to prevent displacement of articles from the table when in folded condition. 45

16. A folding table-wagon comprising a body having a fixed top-section, a movable extension top-section disposed over said fixed top-section, arranged to shift outside one edge of said fixed top-section, means to support said movable top-section in the plane of said fixed top-section, and means to support said fixed top-section, said movable top-section occupying a portion of the area of the fixed top-section, and a similar movable top-section for the other edge of said fixed top-section, the two movable sections being tight together when in non-extended position, said movable sections being provided with edge portions which form a raised margin to prevent displacement of articles from the table when in folded condition. 50

Signed by me at Chicago, Illinois, this 30th day of March, 1915.
